CLOTHES PRESSING MACHINE

Edward Beech, Woodside, N. Y.

Application May 23, 1939, Serial No. 275,170

4 Claims. (Cl. 38—36)

The present invention relates to clothes pressing machines.

Special objects of the invention are to provide a machine of the character stated which can be quickly closed for the pressing operation and which may be actuated to apply increased pressure and to temporarily lock the press in the closed relation.

Other objects are to provide a machine having these advantages and which will be of particularly simple, practical and inexpensive design and construction.

The objects mentioned and other desirable objects are attained by the novel features of construction, combinations and relations of parts constituting the invention, hereinafter fully set forth and broadly claimed.

The drawing accompanying and forming part of the specification illustrates one of the commercial embodiments of the invention. Structure, however, may be modified and changed as regards this particular disclosure all within the true intent and broad scope of the invention as hereinafter defined and claimed.

Fig. 1 is a front elevation of a clothes pressing machine embodying features of the invention, in the open position.

Fig. 2 is a side elevation of the same.

Fig. 3 is a side elevation showing the press closed by the foot pedal operation.

Fig. 4 is a similar view showing the hand toggle thrown over to apply further pressure and to secure the press in this condition.

In the several views, a press is shown consisting of a lower buck or support 5, and a cooperating upper buck or pressure applying member 6, carried by the overstanding lever member 7, hinged at the back at 8, to the base structure 9.

The foot pedal 10, hinged to the base at 11, is connected by a link 12, with a pivot stud 13, on the top buck carrying arm 1, and a spring 14, is shown connected with the foot pedal for lifting and supporting the upper buck in the open raised position illustrated in Figs. 1 and 2.

With the construction described, pressure on the foot pedal will quickly close the press and the pressure on the pedal will determine the pressure applied to the clothes.

For applying additional, heavy pressure, hand toggle mechanism is provided, consisting in the illustration of a pair of toggle links 15, 16, at each side of the machine, the lower links pivoted at their lower ends to the base at 17, the upper links 16, pivoted at their upper ends on the center 13, on the buck carrying arm 1, and the links 55

of each pair being pivotally connected together at 18.

In a preferred construction, the pivot mounting 13, for the upper end of the pedal link 12, and toggle links 16, is a rod journaled in the buck carrying arm and the toggle links 16, are fixed on the ends of the rod protruding at the opposite sides of the arm 1, while the pedal link is simply loosely pivoted on the end of such rod as by means of the adjustable end sleeve 19.

The lower toggle links 15, are shown as having forwardly angled upper end portions 20, which will arch over the pivot rod 13, to carry the intermediate toggle centers 18, forwardly over the rod center 13, as indicated in Figs. 3 and 4.

For swinging the toggle levers forwardly from the Fig. 3 to the Fig. 4 position, thus to carry the toggle centers past the dead center position into the locked condition of Fig. 4, a handle 21, is shown set in a socket 22, extending at an acute angle to the general length of one of the upper links 16.

In the open relation, the handle 21, lays back, projecting to the rear where it is entirely out of the way. As the foot pedal is depressed to lower the upper buck, the lower toggle levers rock the upper toggle levers upwardly and forwardly, thereby swinging the handle 21, up into a position within easy reach of the operator, Fig. 3. The operator then by grasping the handle and swinging it forwardly to the Fig. 4 position, may rock the upper toggle levers, thus to shorten the distance between toggle centers 17, 18, and draw the top buck forcibly downward a further extent. As the arched upper portions 20, of the lower toggle levers carry the toggle centers 18, forwardly over the center 13, the toggles will lock to hold the press closed, until released by upward movement of the handle 21.

As a matter of operating convenience, a handle 21 may be provided at each end of the machine or the handle may be extended in the form of an arch, from the toggle at one end of the machine across the buck carrying arm to the toggle at the opposite end of the machine.

The bucks, either one or both of them, may be heated electrically or otherwise, and may, if desired, be equipped with suitable "steaming" means. The upper end of the pull link 12, may be arched or bowed toward the rear of the machine, so as to provide greater clearance about the rearward edge of the work carrying table 23.

The locking movement of the toggle, that is, from the Fig. 3 to the Fig. 4 position, is deter-

mined in the illustration by a stop pad 24, within the elbow of the lower link 25, coming into engagement with the hub portion of the upper toggle 16, as in Fig. 4.

When the toggle is unlocked, by swinging the handle from the Fig. 4 to the Fig. 3 position, the press is free to open under the power of the press opening spring. While spring 14 may serve for this purpose, it is preferable to provide a coiled spring such as that shown in Figs. 1 and 2, and comprising the two coils 25, engaged about the pivot stud 8, said coils being connected together by an intermediate loop portion 26, bearing on the base and the end portions 27, of the spring coils bearing upward against the underside of the hollow or inverted U-shaped supporting arm 1. This spring lifts the arm directly and usually is sufficient for all purposes without the pedal lifting spring 14.

As foot pressure on the pedal 10 is released, the press will open up from the Fig. 3 to the Fig. 2 position under power of the opening spring or springs 26, 14. In this movement, the toggles will rock in a straightening out direction. The extent of this straightening movement is limited in the illustration by the handle socket 22, coming into engagement with a rubber or similar stop cushion 28, on top of the elbow link 15, as in Fig. 2. By means of such a rubber cushion, objectionable slamming noise of the parts is avoided. These cooperating parts also preferably are so related that the toggles will be stopped in a partly "broken" position as in Fig. 2, so that the foot pedal will be operative to pull the press closed without any opposition from the toggles. The toggles limit and control both the opening movement and the closed position of the press. If the final squeezing pressure is not required, the press movements may be controlled entirely by the foot pedal. At all times however, the toggle mechanism is present and available to furnish the maximum pressure and to lock the press in closed position.

What is claimed is:

1. A clothes pressing machine, comprising co-operating bucks, a lever carrying one of said bucks, a base on which said lever is pivoted, toggle links pivotally connected together and pivotally connected at their free ends with said base and lever respectively, one of said toggle links being angled to rock past a toggle dead center position and having stop means limiting such motion and a cushion stop on one of the toggle links engageable by a portion of the other toggle link for yieldingly stopping and limiting movement of the links in a toggle opening direction to a position less than a fully straightened position of the toggle centers and foot pedal mechanism connected to rock the buck carrying lever in a press closing direction and to freely swing the angularly related toggle links in so doing.

2. A clothes pressing machine, comprising co-

operating bucks, a lever carrying one of said bucks, a base on which said lever is pivoted, toggle links pivotally connected together and pivotally connected at their free ends with said base and lever respectively, one of said toggle links being angled to rock past a toggle dead center position and having stop means limiting such motion and a cushion stop on one of the toggle links engageable by a portion of the other toggle link for yieldingly stopping and limiting movement of the links in a toggle opening direction to a position less than a fully straightened position of the toggle centers and foot pedal mechanism connected to rock the buck carrying lever in a press closing direction and to freely swing the angularly related toggle links in so doing and one of said toggle links having a projecting handle for arbitrary operation of the same.

3. A clothes pressing machine, comprising a base, a buck mounted on said base, a lever arm pivoted on said base, a cooperating movable buck carried by said lever arm, a rock shaft journaled in said lever arm, toggles at opposite sides of said lever arm and including toggle links fixed on said rock shaft and toggle links pivoted to said first mentioned toggle links and pivotally connected to said base, a foot pedal mounted on the base, a link connected with said foot pedal at one end and pivotally connected with the rock shaft at the opposite end, means acting to raise said lever arm, said toggles pivotally connected between the base and lever arm limiting the raising movement of said lever arm, stop means limiting the straightening movement of said toggles in the raising movement of said lever arm to a position less than the fully straightened dead center condition of the toggles to prevent said toggles from acting as stops to prevent the pedal link from lowering the buck carrying lever arm, the toggle links which are pivotally connected with the base having their upper ends forwardly angled to carry the intermediate toggle pivots forwardly over the rock shaft and a handle for rocking said rock shaft and the toggle links fixed thereto.

4. A clothes pressing machine, comprising co-operating bucks, a lever carrying one of said bucks, a base on which said lever is pivoted, toggle links pivotally connected together and pivotally connected at their free ends to said base and lever respectively, one of said toggle links being angled to rock past a toggle dead center position and having stop means limiting such motion, a stop on one of said toggle links engageable by a portion of the other toggle link for limiting movement of the links in a toggle opening direction to a position less than a fully straightened position of the toggle centers and foot pedal mechanism connected to rock the buck carrying lever in a press closing direction and to freely swing the angularly related toggle links in so doing.

EDWARD BEECH.
